CLAIM

The ornamental design of an air conditioner indoor unit, as shown and described.

DESCRIPTION

FIG. 1 is a front elevation view of an air conditioner indoor unit, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof; and,

FIG. 8 is a second perspective view thereof.

The broken lines in the drawings illustrate portions of the air conditioner indoor unit which form no part of the claimed design.
